UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

VARIABLE LINE-SPACER.

1,310,828.

Specification of Letters Patent.

Patented July 22, 1919.

Application filed May 11, 1918. Serial No. 233,835.

To all whom it may concern:

Be it known that I, OTTO A. HOKANSON, a citizen of the United States, residing at Woodstock, in the county of McHenry and State of Illinois, have invented certain new and useful Improvements in Variable Line-Spacers, of which the following is a specification.

This invention relates to typewriters, and more particularly to the platen construction and the line spacing mechanism, and the object of the invention is to provide means by which the platen can be released from the ordinary or normal line spacing mechanism, and varied or set entirely independent of the ordinary line spacing mechanism.

The invention consists in the novel construction, combination, and arrangement of the parts.

In the accompanying drawing—

Figure 1 is a longitudinal section of a platen to which the present invention is applied.

Fig. 2 is a sectional view taken on line 2—2 of Fig. 1; and

Fig. 3 is a perspective of the line spacing ratchet.

In the ordinary operation of a typewriter, the platen is advanced one or more spaces by rotating the platen to space the lines of printing from each other. It may be necessary for the purposes of alinement to vary the line of writing so that it will not come upon any of the lines due to the ordinary line spacing mechanism. The present invention is therefore provided to afford an easily accessible and operable means for disconnecting the platen from the ordinary line spacing mechanism so that the platen can be freely rotated without longitudinal movement thereof, and without longitudinal movement of the shaft upon which the platen is mounted.

In the present invention a platen 1 of well-known form and construction is provided at one end with a bearing member 2, and at the other end with a bearing member 3 having a recess 4 at its outer end and secured to the platen by a suitable fastening means 5. These bearing members 2 and 3 support the platen upon shaft 6 which extends through carriage end plates 7 at the ends of the platen. At the end adjacent the bearing member 2 a knurled knob 8 having a

stem 9 is secured to the shaft by means of a set screw 10. At the other end of the shaft it is formed with a longitudinally extending groove 11, and attached to this end is a knurled knob 12 mounted on a stem 13 which abuts the outside of the carriage plate 7 at this end and is secured to the shaft by means of a set screw 14.

Secured to the inner end of the stem 13 by means of a set screw 15 is a sleeve 16 which fits closely about the shaft 6 and is formed at its inner end, within the recess 4 of the bearing member 3, with a longitudinal slot 17. This sleeve 16 has an annular ridge 18 at a distance from the inside of the carriage end plate 7, and between this ridge and the end of the stem 13 is a bearing sleeve 19 which fits closely around the sleeve 16 and is connected with the carriage end plate 7. Mounted on this bearing sleeve 19, between the plate 7 and the ridge 18 is a line spacing pawl arm 20 and other line spacing parts 21. Mounted on the sleeve 16 inside of the ridge 18 is a line spacing ratchet wheel 22 which extends outwardly beyond the edge of the bearing member 3, and is provided with a slotted circular extension forming tongues 23 which are thinner at their outer edge than they are adjacent the wheel 22 having an inclined wedging surface at the inside of the tongues so that the tongues will fit closely within the recess 4 of the bearing member 3. Also mounted within the recess 4 is a wedging member 24 which is slidable longitudinally on the inner slotted end of the sleeve 16, and the outer face of this wedging member 24 is formed with an inclined surface which cooperates with the inner inclined surface of the resilient tongues 23 of the ratchet wheel 22 so that the tongues can be pressed outwardly into engagement with the bearing member 4, locking the ratchet wheel and pawl together, or can be moved in the other direction, relieving the tongues of this wedging engagement, and thereby allowing the platen to be rotated independently of the ratchet wheel 22.

In order to move the wedging member 24 longitudinally of the shaft 6 and on the sleeve 16, there is a rod 25 which lies in the groove 11 of the shaft 6 having a bent end 26 which engages the wedging member 24 and having a threaded extremity 27 which extends slightly beyond the end of the shaft 110

and beyond the knurled knob 12, and is slightly offset so that the threaded portion is coaxial with the shaft. The end of the stem 13 to which the knob 12 is secured projects outwardly beyond the attached portion of the knob 12 and is formed with an annular groove 28. Mounted on this extension of the stem 13 is a variable line spacing knob 29 which is attached to the stem by means of a screw 30 which has a point projecting into the groove 28 so that the knob 29 can be freely rotated, the knob being also threaded upon the end 27 of the rod 25 so that the rotation of the knob 29 will cause a longitudinal movement of the rod 25, and a corresponding movement of the wedging member 24 to which the inner end of the rod is attached.

In Fig. 2 a line spacing pawl 31 is shown 20 in connection with the line spacing arm 20 by means of which the ratchet wheel 22 is ordinarily moved for line spacing. It should be understood, of course, that the normal line spacing movement may be one 25 or more spaces, but in the operation of the present invention, the normal line spacing movement of the ratchet wheel is of no effect when the wedging member 24 is moved inwardly or out of wedging engagement 30 with the tongues 23 of the ratchet wheel 22.

In order to effect the operation of this variable line spacer, it is necessary only to rotate the line spacing knob 29 relatively to the shaft 6 whereupon the platen 1 is free 35 to move in either direction, and the line spacing wheel 22 remains in position, where it is held by an adjustable spring-pressed roller stop 32. After the platen has been adjusted to the desired position, the line 40 spacing knob 29 is rotated to draw the wedging member 24 against the tongues 23 which will press them outwardly against the walls of the recess 4 of the bearing member 3. In ordinary operation one knob 8 is 45 grasped in one hand, the knob 29 is grasped in the other hand and rotated, and the platen is quickly set by means of the knob 8, after which the connection between the ratchet wheel 22 and the platen is restored by the 50 rotation of the knob 29, and the normal line spacing mechanism may be operated in the ordinary manner.

I claim:—

1. In a variable line spacer, a rotatable 55 platen, means including a ratchet wheel for normally rotating the platen for line spacing, and means including resilient tongues movable radially for directly and frictionally engaging the wheel with the platen so that upon the release the platen is separately rotatable.
2. In a variable line spacer, a rotatable 60 platen, means including a ratchet wheel for normally rotating the platen for line spacing and with resilient tongues projecting

from the wheel, and means for pressing the tongues to engage the platen and lock the platen and wheel together.

3. In a variable line spacer, a rotatable platen with a recessed member at one end, a ratchet wheel for normally rotating the platen for line spacing, a releasable connection between the wheel and the end member comprising spring tongues projecting from the wheel, and means to engage the tongues 75 with the end member.

4. In a variable line spacer, a rotatable platen, a shaft upon which the platen is mounted, a ratchet wheel for rotating the platen, and means including a rotatable 80 knob fixed against axial movement at one end of the shaft for frictionally connecting and for disconnecting the platen and the wheel without longitudinal movement of the wheel, the shaft or platen.

5. In a variable line spacer, a rotatable platen, a shaft to which the platen is attached, a line spacing ratchet wheel, and means including tongues in connection with the wheel and at one end of the shaft for 90 frictionally engaging the tongues with the platen so that they can be rotated together or the platen can be rotated separately.

6. In a variable line spacer, a platen and an attached shaft with which it is rotatable, 95 a line spacing rotatable member, and means including a rotatable knob fixed against longitudinal movement at one end of the shaft and a rod movable longitudinally of the shaft for directly and frictionally connecting and for disconnecting the said rotatable member and the platen.

7. In a variable line spacer, a rotatable platen, a line spacing wheel therefor having 105 projecting spring tongues to engage the platen, a wedging member to press the tongues in engagement with the platen, and means at one end of the platen for moving the wedging member into and out of engaging position.

8. In a variable line spacer, a rotatable platen, a shaft on which the platen is mounted, a line spacing wheel, means for directly connecting the wheel and the platen, means for operating said engaging means comprising a rod movable longitudinally of the shaft at one end thereof, and a rotatable knob threaded on the end of the rod and fixed against movement longitudinally of the shaft.

9. In a variable line spacer, a platen, a shaft upon which the platen is mounted having a longitudinal groove at one end, a line spacing wheel having spring tongues for engaging it with the platen, means for moving the spring tongues into and out of such engagement, and an operating mechanism for said means comprising a rod seated in the groove engaging the said means at one end and a rotatable knob engaging the rod 130

at the other end for moving it longitudinally in said groove.

10. In a variable line spacer, a platen, a shaft on which the platen is mounted, end plates in which the shaft is rotatable, knobs attached to the ends of the shaft outside of the end plates and preventing the longitudinal movement of the shaft, a line spacing ratchet wheel at one end of the platen fixed 5 against longitudinal movement on the shaft and having spring tongues movable to engage the platen, a wedging device rotatable and longitudinally movable on the shaft for engaging the spring tongues, means at one 10 end of the shaft comprising a longitudinally movable rod for engaging the wedging member, and a rotatable knob threaded on the other end of the rod and rotatable but not movable longitudinally with respect to the 15 shaft.

11. In a variable line spacer, a rotatable platen, means including a ratchet wheel for normally rotating the platen in line spacing and with spring tongues formed integral therewith which have an inside wedging surface, a wedging member movable to engage the tongues and press them outwardly to form a frictional engagement with the platen, and means for moving the wedg- 20 25

ing device out of engagement with the spring tongues so that the platen can be rotated entirely free from the ratchet wheel.

12. In a variable line spacer, a rotatable shaft longitudinally grooved at one end, a platen mounted thereon having a recessed bearing member at one end of the platen, a rotating knob for the platen at each end of the shaft, means for fixing the shaft against longitudinal movement, a line spacing ratchet wheel coaxial with the shaft having 30 spring tongues which extend within the recess of the bearing member, a wedging member also within said recess movable longitudinally of the shaft for pressing the spring tongues outwardly in engagement with the 35 wall of the recess, a rod engaging the wedging member at one end movable longitudinally in the slot and having an offset threaded portion projecting from one end of the shaft, a rotatable line spacer knob threaded 40 45 on the end of the rod, and means for attaching the knob to the shaft for permitting the rotation of the knob and preventing its movement longitudinally of the shaft.

In testimony whereof I have signed my 50 name to this specification on this 8th day of May, A. D. 1918.

OTTO A. HOKANSON.
